COMBINED CHAIR AND IRONING BOARD

John H. Haney and Maurine K. Haney,
Fort Dodge, Iowa

Application January 23, 1933. Serial No. 653,096

12 Claims. (Cl. 155—43)

The object of our invention is to provide a combined chair and ironing board which is simple, durable and comparatively inexpensive to manufacture.

- 5 A further object of our invention is to provide a chair formed of elements which may be readily extended from their normal position to a position serving as an ironing board, supporting elements for the ironing board being foldable, collapsible and slidable relative to the frame of the device so that they can all be concealed within the frame when the device is used as a chair.
- 10 More particularly, it is our object to provide a combined chair and ironing board consisting of a chair frame with a back element and a seat element hinged together and arranged to swing forwardly to a substantially level position to serve as an ironing board, suitable supporting means being normally folded within the chair frame and capable of extension to a supporting position for the ironing board.

- 15 Still another object is to provide a seat extension element hinged to the seat element so that the back element, seat element and seat extension element provide an ironing board of practical length and an intermediate supporting element being hinged to the chair frame and normally assuming a position under the seat element and seat extension element.

- 20 Still a further object is to provide means for supporting the outer end of the ironing board in the form of a slide element having a slide extension element hinged thereto with a collapsible post member connected with the outer end of the slide extension element.

- 25 Still a further object is to provide means for connecting the post member at different distances from the end of the seat extension element, the slide element permitting such adjustment.

- 30 With these and other objects in view our invention consists in the construction, arrangement and combination of the various parts of our device, whereby the objects contemplated are attained as hereinafter more fully set forth, pointed out in our claims and illustrated in the accompanying drawing, in which:

Figure 1 is a side elevation of our combined chair and ironing board showing it in ironing position.

- 35 Figure 2 is a front elevation of the same.

Figure 3 is a sectional view on the line 3—3 of Figure 1 showing a bottom plan view of the elements which form the ironing board.

- 40 Figure 4 is a vertical sectional view on the line 4—4 of Figure 2 showing the parts collapsed, how-

ever, instead of in the extended position of Figures 1 and 2; and

Figure 5 is a perspective view showing the parts in their normal or chair forming position.

On the accompanying drawing, we have used 60 the reference character A to indicate generally a chair frame. The frame A consists of side frame elements 10, front cross frame elements 12 and a rear cross frame element 14.

Pivoted at 16 to the upper ends of the side 65 frames 10 is a back element 18. Hinged at 20 to the lower end of the back element 18 is a seat element 22. A seat extension element 24 in turn is hinged at its forward edge to the forward edge of the seat element 22, as indicated at 26. The 70 elements 18, 22 and 24 are adapted to form an ironing board or surface when in their extended position, as will hereinafter be more fully described.

Hinged at 23 to the cross bar 12 of the chair 75 frame is an intermediate supporting element 25. Its rear end normally rests on a cross bar 15 of the chair frame.

Slidable on side bars 28 is a slide element 30. It consists of a pair of side bars and a cross bar 80 30a. Pivoted at 32 to the slide element 30 is a slide extension element 34.

Hinged to the slide extension element 34, as at 36, is a depending post element 38. It is provided with a cross bar 38a to which is hinged at 40, 85 an upstanding primary post element 42. Hinged at 44 to the post element 42 is a secondary upstanding post element 46.

Hinged at 48 to the cross bar 12 of the chair frame is a closure panel or door 50. It is adapted 90 to be closed when the ironing board is collapsed and the device is used as a chair, as shown in Figure 5.

This completes the description of the parts of our combined chair and ironing board with the 95 exception of a few fastening elements which will be described under the following heading.

Practical operation

Referring to Figures 4 and 5, it will be noted 100 that the elements 18, 22, 24, 30, 34, 38, 42 and 46 are all in collapsed or folded position and that the door 50 encloses the elements 30, 38, 42 and 46. When it is desired to use the device as an ironing board, the elements 18, 22 and 24 can first 105 be swung to the dotted line position of Figure 1 and then raised to the full line position. The element 25 can then be swung to its supporting position.

The door 50 can now be opened and the slide 110

element 30 with the elements 34, 38, 42 and 46 supported thereon can be slid forwardly.

The elements 34, 38, 42 and 46 can then be unfolded to the dotted line position of Figure 1 and then further unfolded to their fully extended position as shown by full lines. To retain them in this position, the following described fastening means is utilized.

An ordinary hook such as used on a screen door 10 and its coacting screw eyes are indicated at 52 for holding the elements 38 and 42 rigid with respect to the forward end of the element 34. The cross bar 38a being set lower than the upper edge of the element 34 provides a shoulder to assist in 15 limiting the elements 38 and 42 to a right angle position with respect to the element 34.

A turn button 54 is utilized to keep the elements 42 and 46 in alinement with each other and a hook 56 and its coacting screw eyes are used to secure 20 the upper end of the element 46 to the element 42. Thus the ironing board, consisting of the elements 18, 22 and 24, is effectively supported intermediate its length by the element 24 and at its outer end by the elements 38, 42 and 46, which 25 when extended form a post member.

The upper end of the element 46 is provided with a dowel adapted to selectively enter openings 58 of the element 24. For instance, a full line and a dotted line position are shown in Figure 1. A plurality of screw eyes is provided for the hook 56 to accommodate the post member in any of its three adjusted positions. The slide element 30, of course, permits such adjustment since it merely slides into the chair frame when 35 the post member is adjusted toward the frame.

The purpose of this adjustment is so that ordinarily the ironing board is supported at its extreme outer end, but when it is desired to iron clothing which should encircle the end of the 40 board, the post can be adjusted so that more or less overhang of the small end of the ironing board is thus secured.

Some changes may be made in the construction and arrangement of the parts of our device without departing from the real spirit and purpose 45 of our invention, and it is our intention to cover by our claims, any modified forms of structure or use of mechanical equivalents, which may be reasonably included within their scope.

We claim as our invention:

1. In a combined chair and ironing board, a chair frame, a back element pivoted to the upper end thereof, a seat element hinged at its back edge to the lower edge of said back element, a seat extension element normally positioned beneath said seat element and hinged to the forward edge thereof and means for supporting said three elements in a substantially level position extending forwardly from said chair frame, said means including a slide element slidably mounted in said chair frame and a post member connected with said slide element and detachably connected with said seat extension element.

2. In a combined chair and ironing board, a chair frame, a back element pivoted to the upper end thereof, a seat element hinged at its back edge to the lower edge of said back element, a seat extension element normally positioned beneath said seat element and hinged to the forward edge thereof and means for supporting said three elements in a substantially level position extending forwardly from said chair frame, said means including a slide element slidably supported on said seat frame, a slide extension element having one end connected to said slide ele-

ment and a post member, said post member being connected with the other end of said slide extension element and detachably connected with said seat extension element.

3. In a combined chair and ironing board, a chair frame, a back element pivoted to the upper end thereof, a seat element hinged at its back edge to the lower edge of said back element, a seat extension element normally positioned beneath said seat element and hinged to the forward edge thereof and means for supporting said three elements in a substantially level position extending forwardly from said chair frame, said means including a slide element slidably mounted in said chair frame and a collapsible post for supportingly engaging said seat extension element, said post being normally collapsed to a position on said slide element and supported thereby.

4. In a combined chair and ironing board, a chair frame, a back element pivoted to the upper end thereof, a seat element hinged at its back edge to the lower edge of said back element, a seat extension element normally positioned beneath said seat element and hinged to the forward edge thereof and means for supporting said three elements in a substantially level position extending forwardly from said chair frame, said means including a slide element supported on said chair frame, a slide extension element hinged thereto and normally supported thereby and a collapsible post member normally collapsed and supported by said slide element, said post member in its extended position supportingly coacting with said seat extension element.

5. In a combined chair and ironing board, a chair frame, a back element pivoted to the upper end thereof, a seat element hinged at its back edge to the lower edge of said back element, a seat extension element normally positioned beneath said seat element and hinged to the forward edge thereof, means for supporting said three elements in a substantially level position extending forwardly from said chair frame, said means including a slide element slidably mounted in said chair frame and a collapsible post for supportingly engaging said seat extension element, said post being normally collapsed to a position on said slide element and supported thereby and an openable door in the front of said chair frame for concealing said slide element and collapsible post when they are slid to position within said chair frame.

6. In a combined chair and ironing board, a chair frame, a back element pivoted to the upper end thereof, a seat element hinged at its back edge to the lower edge of said back element, a seat extension element normally positioned beneath said seat element and hinged to the forward edge thereof and means for supporting said three elements in a substantially level position extending forwardly from said chair frame, said means including a slide element supported on said chair frame, a slide extension element pivoted thereto and a collapsible post member having a depending post element and an upstanding post element hinged to said slide extension element.

7. In a combination chair and ironing board, a chair frame, a back element and a seat element connected with said chair frame and extensible forwardly from the back of said frame to a horizontal position serving as an ironing board and collapsible means normally positioned within

- 5 said chair frame below said seat element to support said ironing board when said collapsible means is in its extended position, a portion of said means being confined for horizontal sliding movement only and another portion thereof being hinged to the outer end of said first portion and extensible to a vertical supporting position.
- 10 8. In a combination chair and ironing board, a chair frame, a back element and a seat element connected with said chair frame and extensible forwardly from the back of said frame to a horizontal position serving as an ironing board, collapsible means normally positioned within said chair frame below said seat element
- 15 10 to support said ironing board when said collapsible means is in its extended position, a portion of said means being horizontally slidably and another portion thereof being hinged to said first portion and extensible to a vertical supporting position and means for causing coaction of said second portion at different distances from the outer end of said back element and said seat element when extended to ironing position.
- 20 25 9. In a combined chair and ironing board, a chair frame, a back element pivoted to the upper end thereof, a seat element hinged at its back edge to the lower edge of said back element, a seat extension element normally positioned beneath said seat element and hinged to the forward edge thereof and means for supporting said three elements in a substantially level position extending forwardly from said chair frame, said means including an intermediate supporting element normally positioned below said seat element and said seat extension element and hinged at its forward edge to said chair frame, said means including a slide element slidably mounted in said chair frame and a post member connected with said slide element and selectively detachably connected with said seat extension element at different distances from the forward end thereof.
- 30 35 40 45 50 55 60 65 70 75 80 85 90 95 100 105 110 115 120 125 130 135 140 145 150
10. In a combined chair and ironing board, a chair frame, a back element pivoted to the upper end thereof, a seat element hinged at its back edge to the lower edge of said back element, a seat extension element and means for supporting said elements in a substantially level position extending forwardly from said chair frame, said means including a slide element slidably mounted in said chair frame and a post member connected with said slide element and detachably connected with said seat extension element.
11. In a combined chair and ironing board, a chair frame, a back element pivoted to the upper end thereof, a seat element hinged at its back edge to the lower edge of said back element, a seat extension element and means for supporting said elements in a substantially level position extending forwardly from said chair frame, said means including a slide element slidably mounted in said chair frame and a collapsible post for supportingly engaging said seat extension element, said post being normally collapsed to a position on said slide element and supported thereby.
12. In a combined chair and ironing board, a chair frame, a back element pivoted to the upper end thereof, a seat element hinged at its back edge to the lower edge of said back element, a seat extension element, means for supporting said elements in a substantially level position extending forwardly from said chair frame, said means including a slide element slidably mounted in said chair frame and a collapsible post for supportingly engaging said seat extension element, said post being normally collapsed to a position on said slide element and supported thereby and an openable door in the front of said chair frame for concealing said slide element and collapsible post when they are slid to position within said chair frame.
